UNITED STATES PATENT OFFICE.

LEWIS C. MYERS, OF FREEPORT, NEW YORK, ASSIGNOR TO ROYAL TYPEWRITER COMPANY, INC., OF NEW YORK, N. Y., A CORPORATION OF NEW YORK.

TYPEWRITING MACHINE.

Application filed April 30, 1926. Serial No. 105,776.

This invention relates to an improved form of paper table and the mounting of the same. Its object is to provide a paper table which can be stamped out of one piece of sheet metal and supported on the carriage frame without the necessity of any particular additional parts being provided. While particularly adapted for the Royal portable machine and illustrated in connection therewith, it is to be understood that it is of value in other types of machines. The details of the invention will be apparent from the following description.

In the drawings:

Figure 1 is a top plan view of a portion of a carriage of a typewriting machine with the paper table moved to its rear position.

Figure 2 is an end elevation of the paper table detached and before being placed in position on the machine.

Figure 3 is an end elevation of the carriage with the paper table attached and in operative position.

Figure 4 is a similar view with the paper table swung to its rear inoperative position.

Figure 5 is a side elevation showing the mounting of the roll carrying bail.

The drawings disclose side frames A of a carriage in which is mounted a platen B which has front feed rolls C and rear feed rolls D cooperating therewith, and a paper apron E carrying a scale F at its upper edge. The rod G and arms H comprise a roll carrying bail and the arms are mounted to turn with a rod K mounted in the side frames of the carriage. A spring L acts to hold this roll carrying bail in either of its positions. There is also disclosed the margin stop bar M carried by the carriage side frames and having margin stops N adjustable thereon. All of these parts are or may be of old or any desired construction.

The paper table 1 is curved in form and has at each end portions 2 of reduced size which terminate in arms 3 that are bent at approximately right angles to the plane of the table 1. The lower end of each arm is divided by a long slot into two legs 4 and 5, the upper end 6 of the slot being circular in form. The leg 4 is much thinner at the point 7 where it joins the body of the arm 3 than is the leg 5. When the paper table has been stamped out and bent to the form shown in Figure 2, it is ready to be applied to the machine.

This is done by causing the legs 4 and 5 to straddle the rod K which supports the paper table just inside of the arms H of said bail. The forward leg 4 of each arm 3 is then bent backwardly until its lower end contacts with the leg 5 and the parts occupy the position shown in Figures 3 and 4. The leg 5 is of such dimensions that it does not bend during this operation and acts as a stop to limit the movement of the leg 4. 60 The rod K then serves as a pivot for the paper table about which it can move from the normal position shown in Figure 3 to the rearward position shown in Figure 4 whenever it is desired to obtain more ready 65 access to the margin stops or for any other reason.

The forward leg 4 is provided with a stop portion 8 which is so formed that when the parts are positioned and the table is moved 70 rearwardly to the Figure 4 position, thus stop 8 will contact with the underface of the margin stop rod M and limit the movement of the paper table in this direction. The forward movement of the paper table is 75 limited by a flange 9 which engages the upper edge of a scale F. The rear edge of the paper table may also be provided with a flange 10.

The paper table is held against accidental 80 displacement from either of its positions by the following means: A spring 11 has an intermediate portion coiled about a stud 12 carried by one of the side plates of the carriage and one end 13 of this spring engages 85 the under forward edge of the margin stop bar M. The other end of the spring 11 extends rearwardly over the top of the margin stop bar and is provided with a return 90 bend so that the spring constitutes a long 95 open end loop 14, as clearly shown in Figure 4. The arm 3 of the paper table at this side is provided with an inwardly extending stud 16 which is provided with a groove 15 in 100 which engage both the upper and lower parts of the loop 14. It is obvious that when the paper table is moved from either of the extreme positions shown in Figures 3 and 4, that the stud 16 will move upward from such position and this will bend the spring 11 and tension it to resist such movement. The loop is of such length that both parts 105 thereof will engage in the groove 15 in both extreme positions of the paper table as shown in Figures 3 and 4.

The arms 3 may be flanged as indicated at 17 in order to add strength and stability to the construction. The arms 3 are the same at both sides of the machine so that a stop 5 is provided for the rearward movement of the table at each side.

The broad combination of a paper apron provided with a scale immediately adjacent a margin stop with a rearwardly swinging 10 paper table which is moved to expose the stop so that it can be set by direct reference to the scale is not claimed herein but forms the subject matter of an application of Edward B. Hess, Serial No. 133,002, filed September 1, 1926.

It is obvious that the invention may be embodied in typewriting or similar machines of widely varying characteristics and that the precise details of the embodiment may be 20 varied considerably without departing from the spirit of the invention which is to be regarded as limited only by the scope of the appended claims.

I claim:

25 1. A paper table mounted at the rear of the platen formed of a single piece of sheet metal and having at each end an arm bent at substantially right angles to the body of the table, each arm being provided with an open ended slot forming two legs adapted to receive between the same a supporting means about which the table may swing to operative or inoperative position.

30 2. A paper table formed of a single piece of sheet metal and having at each end an arm bent at substantially right angles to the body of the table, each arm being provided with an open ended slot forming two legs adapted to receive between the same a supporting means, one of said legs being adapted to be bent toward the other to close the lower end of the slot sufficiently to prevent displacement of the table from its position when mounted on said supporting 40 means.

35 3. A paper table formed of a single piece of sheet metal and having at each end an arm bent at substantially right angles to the body of the table, each arm being provided with an open ended slot forming two legs adapted to receive between the same a supporting means, one of said legs being adapted to be bent toward the other to close the lower end of the slot sufficiently to prevent displacement of the table from its position when mounted on said supporting 50 means, and the inner end of the slot being circular to permit the table when mounted to be moved from one position to another.

60 4. A paper table formed of a single piece

of sheet metal having a curved body portion with a flanged front edge, and having at each end an arm bent at substantially right angles to said body portion and divided by a slot into two legs adapted to receive between them a supporting means about which the table may move from one position to another, and the front leg being formed with a stop portion to determine the extent of movement in one direction. 65

5. In a typewriting machine having a carriage provided with a margin stop bar and a rod extending between the side plates of the carriage, a paper table formed of a single piece of sheet metal having an arm at 70 each end divided into two legs adapted to receive between them said rod, one of said legs adapted to be bent toward the other to retain the table in position and permit movement thereof about the rod from operative so to inoperative position, said leg also being provided with a stop portion to engage the margin stop bar and limit the movement of the table in one direction. 75

6. In a typewriting machine having a carriage and a rod extending between the side plates thereof, a paper table formed of a single piece of sheet metal and having at each end an arm divided by a slot into two legs adapted to receive between them said rod, one of said legs being adapted to be bent towards the other to retain the table in position, and the inner end of the slot being circular so that the table may rotate upon said rod from one position to another. 85

7. In a typewriting machine having a carriage, a paper table mounted therein to move about an axis from one position to another, a spring having one end held against movement in one direction and the other end bent 90 to form an open ended loop parallel to a plane passing through said axis, and a stud on the paper table engaged by said loop. 95

8. In a typewriting machine having a carriage provided with a margin stop bar and a rod supporting the roll carrying bail, a paper table having legs adapted to fit over said rod and permit rotary movement of the table, a stud on the carriage, a spring coiled about said stud and engaging the margin stop bar to prevent movement of the spring about the stud, one end of the spring being bent to form an open ended loop parallel to a plane passing through the axis of the rod, and a stud on the paper table engaged by said loop. 105

In testimony whereof I have hereunto subscribed my name.

LEWIS C. MYERS.
